US0D1071929S

(12) **United States Design Patent** (10) **Patent No.:** **US D1,071,929 S**
(45) **Date of Patent:** **** Apr. 22, 2025**

(54) **NETWORK DEVICE**

(71) Applicant: **Cisco Technology, Inc.**, San Jose, CA (US)

(72) Inventors: **Nicholas James Kawamoto**, Novato, CA (US); **Joesph F. Jacques**, Austin, TX (US); **Edward John Kliewer**, Sunnyvale, CA (US); **Parmis Taidy**, Tampa, FL (US); **Brad Andrew Palladino**, Oakland, CA (US)

(73) Assignee: **Cisco Technology, Inc.**, San Jose, CA (US)

(**) Term: **15 Years**

(21) Appl. No.: **29/914,773**

(22) Filed: **Oct. 20, 2023**

Related U.S. Application Data

(63) Continuation-in-part of application No. 17/554,886, filed on Dec. 17, 2021, now Pat. No. 11,940,661.

CLAIM

The ornamental design for a network device, as shown and described.

DESCRIPTION

FIG. 1 is a top, front, left-side perspective view of a network device;

FIG. 2 is a top, front, right-side perspective view thereof;

FIG. 3 is a top, back, left-side perspective view thereof;

FIG. 4 is a top, back, right-side perspective view thereof;

FIG. 5 is a front view thereof;

FIG. 6 is a back view thereof;

FIG. 7 is a left-side view thereof;

FIG. 8 is a right-side view thereof;

FIG. 9 is a top view thereof; and,

FIG. 10 is a bottom view thereof.

The dashed broken lines depict portions of the network device that form no part of the claimed design.

1 Claim, 10 Drawing Sheets
